UNITED STATES PATENT OFFICE.

BENJAMIN TEIPEL, OF COVINGTON, KENTUCKY, ASSIGNOR TO THE LIGOWSKY CLAY PIGEON COMPANY, OF CINCINNATI, OHIO.

TARGET-TRAP.

SPECIFICATION forming part of Letters Patent No. 329,974, dated November 10, 1885.

Application filed August 6, 1885. Serial No. 173,690. (No model.)

To all whom it may concern:

Be it known that I, BENJAMIN TEIPEL, a citizen of the United States, residing at Covington, in the county of Kenton and State of 5 Kentucky, have invented certain new and useful Improvements in Target-Traps, of which the following is a specification.

My invention relates more especially to target clamps or holders in traps for throwing 10 artificial targets of the class which are intended to sail or fly through the air with a motion analogous to that of a bird on the wing. Such targets have heretofore been provided with a tongue secured thereto by glue 15 or otherwise and adapted to be grasped by the target-clamp. These tongues interfere with the economical packing of the targets for shipment and are liable to be accidentally detached before the target is used. To avoid 20 these objections target holders or clamps have been invented and placed upon the market which are designed to grasp the pigeon or target itself; but such holders are generally complicated, and therefore objectionable.

25 The object of my invention is to provide a simple and inexpensive target-holder especially adapted to throw targets which are free from such tongues or flanges as will interfere with close packing for shipment or impede the flight of the target, and which may be applied to any approved form of traps.

In the drawings, Figure 1 is a perspective view of a target-holder embodying my invention, the holder being shown as pivotally attached to the throwing-arm and carrying a target. Fig. 2 is a perspective view showing the target-holder rigidly attached to the throwing-arm; and Fig. 3 is a perspective view of a target especially adapted for use 35 with my improved target-holder.

A represents the throwing-arm of a target-trap. B represents a target-holder consisting of a spring, preferably flat, whose general outline is such as to embrace a portion of the periphery of the target to be thrown. This 45 holder may be rigidly attached to the throwing-arm, but I prefer to attach it pivotally, as shown in Fig. 1, so that the target-holder will have a sweep independent of that of the throwing-arm. In this target-holder are perforations b, adapted to take over lugs c upon the target C. The target may be of any approved 50 form and material.

If the holder is pivotally attached to the throwing-arm, a lug or stop, a, should be 55 placed upon the latter to arrest the sweep of the holder at the proper moment for the delivery of the target. When the holder is rigidly connected with the throwing-arm, the recoil of the latter may be depended upon to 60 release the target.

I claim—

1. A target-holder consisting of a spring adapted to embrace a portion of the perimeter of the target and provided with perforations 65 adapted to take over lugs upon the target, substantially as and for the purpose specified.

2. The combination, with the throwing-arm of a target-trap, of a target-holder consisting of a spring adapted to embrace a portion of the perimeter of the target and provided with perforations, and a target 70 provided with lugs to enter into such perforations, substantially as and for the purpose specified.

BEN. TEIPEL.
